INDICATING APPARATUS FOR LOCOMOTIVE BACK PRESSURE

Application filed October 21, 1925. Serial No. 63,827.

Our invention relates to indicating apparatus for locomotive back pressure, and is particularly useful for indicating to the engineer how he should move the reverse lever 5 in order to maintain a substantially constant back-pressure.

It will, of course, be understood that as the speed of the locomotive increases it is customary to hook up or "hook back" the reverse lever in order to use the steam expansively and to reduce back-pressure in the exhaust line. Applicants have found, jointly with Mr. R. W. Retterer, as disclosed in pending application No. 319,062, filed Aug. 22, 1919, 15 that for any given locomotive there is one particular back-pressure value, which, if held constant by adjusting the cut-off, will insure the development of maximum draw bar pull with the greatest degree of economy and efficiency. In other words if the back-pressure attendant upon the most efficient operation of the locomotive be ascertained and the locomotive be operated constantly at that back-pressure the efficiency of operation will 20 always be at a maximum.

The primary object of our invention, therefore, is the provision of what might be termed a "cut-off position change indicator", that is, a mechanism which will give a positive indication at all times as to whether or not the reverse lever is in the best position for efficient operation of the locomotive, and further, to indicate directly whether the reverse lever should be "hooked up" or "hooked down", 30 that is whether the cut-off should be shortened or lengthened, to reach the point of greatest efficiency for the particular conditions existing at the time. Still another object of the invention is to indicate when a 35 state of vacuum has been reached in the cylinders when the locomotive is drifting.

A further object of the invention is the provision of means for accomplishing the foregoing ends which shall at the same time be easy of installation, inexpensive in upkeep and repair, readily adjustable to suit the requirements of the individual locomotive, stable in operation, and extremely rugged to withstand the shocks incident to the heavy 45 exhaust pressure pulsations.

How we attain the foregoing advantages and others which will occur to those skilled in the art will appear from the following description of the present preferred embodiment of our invention and its operation, reference being had to the accompanying drawings, wherein:

Fig. 1 is a longitudinal section of the gauge proper;

Fig. 2 is a cross section of the same, taken on the line 2—2 of Fig. 1;

Fig. 3 is a view partly in section, of the pressure impulse dampener used in conjunction with the gauge; and

Fig. 4 is a diagrammatic view of a locomotive with our invention applied thereto.

Referring now to Fig. 1, in which the letter A refers to the lower, or actuating part of the gauge as a whole, and B the upper, or indicating part, back-pressure is admitted through the pipe 2, from the choke or impulse dampener D (shown in Figs. 3 and 4), into the pressure chamber 3, which is a space bounded by the head 4 and the sylphon or flexible bellows diaphragm 5. The pressure in this chamber 3, acts to expand the sylphon 5 against the counter-balancing pressure of the spring 11 later referred to. The movable end of the sylphon is attached to the annular block piece 6 mounted fast on the rod 7 and adapted to abut against the shoulder 8 of the collar 9. This collar 9, when the back-pressure acting against it through the sylphon 5 and associated parts is less than a certain predetermined amount is held by a rib or shoulder 10 against the pressure of spring 11 supported by the collar 12 threaded on the shank or spindle 13. Collar 12 may be screwed one way or the other, by means of the key pin 14 fitting the holes 14^a, to adjust the compression of spring 11.

To prevent pulsating movements and undue shocks in the apparatus from the changes in pressure caused by the intermittent exhaust of the locomotive, we have provided, in addition to the pressure impulse dampener D (elsewhere described in detail), a dashpot composed of the piston 15, fastened to one end of the rod 7 and operating in the cylinder 16. There is provided a port 17, in one end of the

cylinder, opening to the atmosphere, and the usual restricted passage 18 through the piston. Lubrication is provided by the oil cup 19.

5 The combination in our device of a sylphon and dashpot construction makes it both rugged and accurate, the dashpot piston serving to dampen sudden movements of the device, while at the same time the sylphon acts 10 with sufficient force to move the indicator with accuracy against any friction that may exist between the dashpot piston and cylinder.

Within the sylphon 5 is a light spring 20 abutting against the face 21 inside the cap 15 4 and acting against the portion 6^a of the block 6 to keep the block against the shoulder 8 when the back pressure is substantially at zero.

20 The indicator B, of the apparatus (see Figs. 1 and 2) is of the following construction: An arm 22, supported by a pivot-member 23 mounted on the pins 24, carries at its end a pointer 25 adapted to move over the dial 26. Below the pivot line the pivot-member 25 carries a roller 27 mounted on the pin 27^a, adapted to engage an annular groove 28 in the block 6. A spring 29 on one pivot pin 24 exerts a slight pressure on the end of member 23 to keep the indicator arm 22 in proximity 30 to the dial. Suitable marks 30 and 31 on the dial indicate respectively zero back-pressure and "hold" position, hold position being an index of the amount of back-pressure when cut-off is adjusted to the position for greatest economy and efficiency of operation. Suitable directions to the engineman may also be marked on the dial, such as the words "Hook down" placed between the points 30 and 31, "Hook up" placed to the right of point 31, 35 and "Vacuum" placed to the left of point 30.

40 The gauge has a base portion 32 with bolt holes 33 for convenient mounting on a bracket or other suitable support in the cab of the locomotive. Fig. 4 shows the indicator mounted on a locomotive within the ready observation of the engineer and illustrates the connection of pipe 2 through the dampener D to all four exhaust cavities of the cylinders through piping 34.

45 The pressure choke or exhaust impulse dampener D, which we term a "uniflow fitting", (see Fig. 3), performs the function of initially "ironing out" to a large extent the variable pressure impulses of the exhaust before the admission of such pressure to the sylphon chamber 3 of the gauge proper, and to this end it is inserted in the pipe 2 between the locomotive exhaust passages and the gauge as shown in Fig. 4. This choke D is of a 50 very simple and rugged construction, easy to assemble and to take apart for cleaning, and constructed of a minimum number of parts. The casing or wall 35 is equipped at each end with a cap piece 36, and centered by these 55 caps, within the chamber 37 thus formed, is a

baffle or screen 38 having a ring 39 within it through which the bolt 40 passes, this bolt being extended through both caps and clamping the whole structure firmly together by means of the nut 41. The two caps 36 are 70 identical, each having a lateral opening or pipe connection 42 which becomes a restricted passage or nozzle 43 toward the inside. A valuable feature of the dampener, bearing on the ease of assembly and actual installation 75 of the device, is the construction of the cap-pieces which may be turned through any degree relatively to each other or to the cylindrical shell while at the same time the planes of the inlet and outlet ports remain parallel, so thus obviating the necessity for elbows and other fittings in the connecting piping.

80 The construction of this dampener, per se, being a separate invention, forms the subject-matter of a divisional application, Serial No. 402,556, filed October 26th, 1929.

85 The operation of the complete apparatus is as follows:

90 Back-pressure, admitted from the exhaust ports of the cylinders through piping 34 to pipe 2, must first pass through the impulse dampener D, to which it is admitted through one of the openings 42. The impulses pass through the choke passage or port 43, then through the openings of cylindrical screen 95 38 into the chamber 37, back into the centre of the screen again on the other side of ring 39, and out through the other port 43, which, widening outwardly, acts to reduce the velocity of the now smoothed-out pressure 100 stream as it leaves the dampener.

105 The damped exhaust, or mean average exhaust pressure, is next passed through the pipe 2 to the actuating mechanism A of the gauge in the locomotive cab. When the pressure enters the chamber 3 the sylphon 5 expands, moving to the left the block 6, the collar 9 and the rod 7, against the pressure of the spring 11, the dashpot on the remote end of rod 7 assisting in dampening any pulsating movement remaining in the exhaust pressure line. The roller 27 engaging the groove in the block 6 will be moved a corresponding distance and the pointer 25 will be moved over the dial towards the right. 115

120 Let us suppose that the particular locomotive to which the device is applied operates most efficiently with a back-pressure of ten pounds. For this installation, collar 12 should be adjusted on the spindle 13 to give spring 11 the proper resistance to balance the pointer at the mark 31 against a back-pressure of 10 pounds per square inch. This mark 31 is "hold" position, and in actual 125 operation when the pointer moves up to that point it will indicate to the engineman that the reverse lever is in the proper position for the conditions then existing.

130 After the tension on spring 11 has been thus properly adjusted, when the locomotive is

started, the reverse lever will be left in the position of longest cut-off, or "down in the corner" as it is termed, until the pressure in chamber 3 builds up to 10 lbs. per square inch, in which time the pointer will have moved 5 up to the "hold" point 31 on the dial. Should back-pressure increase beyond this point, the pressure in chamber 3 will increase causing a movement of the pointer to the right of point 31 and giving a "hook up" indication 10 to the engineer, who then hooks up the reverse lever, shortening cut-off until the pointer returns to hold position, the shortening of the cut-off, of course, acting to reduce 15 the back-pressure. The reverse lever will be held in that position until the pressure changes again at which time it will be re-adjusted as indicated by the pointer, hooked up if the pointer has moved again to the 20 right of mark 31, or hooked down if it has moved to the left. Guided by these indications the engineman will so operate the reverse lever as to maintain the pointer 25 at the mark 31 on the dial, and in consequence 25 the engine will at all times be operating at maximum efficiency.

For positive values of back-pressure the operation of the apparatus will thus be seen to be dependent upon the relation of the 30 pressure in chamber 3 and the opposite pressure of the spring 11, but when the back-pressure falls below zero, viz., when a partial vacuum is created in the locomotive exhaust passages, (as when the locomotive is 35 drifting) the sylphon 5 is contracted, pulling the block 6 away from the shoulder 8 against the pressure of the spring 20, and moving the pointer below the mark 30 on the dial. This indicates to the engineman that the throttle 40 opening should be greater or a longer cut-off should be used, to destroy the vacuum.

We claim:—

1. An indicator by which to regulate locomotive valve-gear cut-off adjustment comprising a dial having cut-off change indications, an arm co-operating therewith, actuating mechanism for the arm under the influence of the locomotive back-pressure, means yieldingly acting on said mechanism 45 in opposition to said pressure, and damping means co-operating with the mechanism and yieldingly resistive to changes of position thereof.

2. An indicator by which to regulate locomotive valve-gear cut-off adjustment comprising a dial having cut-off change indications, an arm co-operating therewith, actuating mechanism for the arm under the influence of the locomotive back-pressure, 50 means yieldingly acting on said mechanism in opposition to said pressure, and damping means co-operating with the mechanism and yieldingly resistive to changes of pressure.

3. A pressure gauge comprising, in combination, a movable member yieldingly resis-

tive to pressure in one direction of its movement, means co-operating therewith and yieldingly resistive to changes of pressure in either of two opposite directions of movement of said member, and an indicator actuated by said member.

4. In a locomotive, mechanism for indicating change of cut-off necessary for efficient operation comprising a dial having cut-off change indications, an arm cooperating therewith, and actuating mechanism engaging the arm and consisting of oppositely-acting tension devices and movable means positioned by said tension devices and actuated by the locomotive back-pressure.

5. Mechanism of the character described comprising in combination with an indicator, actuating mechanism therefor comprising a reciprocable member, a flexible member adapted to move it in response to variations in locomotive back-pressure, and a tension device adapted to resist such movement, said reciprocable member having freedom of movement beyond the range of said tension device.

6. Mechanism of the character described comprising in combination with an indicator, actuating mechanism therefor comprising a reciprocable member, a flexible member adapted to move it in response to variations in locomotive back-pressure, a tension device adapted to resist such movement, and damping means directly associated with the reciprocable member.

7. In indicating apparatus, the combination of a movable member, indicating means actuated thereby, means for admitting pressure fluid to said member, means for damping the movement of said member, and means for damping impulses in the pressure fluid admitted to the member.

8. In indicating apparatus, the combination of a flexible bellows diaphragm, indicating means actuated thereby, inlet means for admitting back-pressure to said diaphragm, a dampener comprising a dash-pot and piston with one of said elements connected to said diaphragm, and choke means co-operating with said inlet means for dampening the impulses of the back-pressure admitted.

9. In apparatus for indicating required changes in locomotive cut-off, the combination, with an indicator, of operating mechanism therefor comprising a sylphon, a movable rod, a block fast thereon attached to the sylphon and in operative engagement with the indicator, a collar loose on said rod, a spring acting on the collar to force it against said block, and a stop in the path of said collar.

10. In apparatus for indicating required changes in locomotive cut-off, the combination, with an indicator, of operating mechanism therefor comprising a sylphon, a movable rod, a block fast thereon attached to the

sylphon and in operative engagement with the indicator, a collar loose on said rod, a spring acting on the collar to force it against said block, a stop in the path of said collar, and a dash-pot piston on said rod.

- 5 11. In apparatus for indicating required changes in locomotive cut-off, the combination, with an indicator, of operating mechanism therefor comprising a sylphon, a movable rod, a block fast thereon attached to the sylphon and in operative engagement with the indicator, a collar loose on said rod, a spring acting on the collar to force it against said block, a stop in the path of said collar, and a second spring acting against said block in a direction opposite to said first spring.

- 10 12. In apparatus of the character described, the combination, with an indicator, of operating mechanism therefor comprising a sylphon, means for admitting locomotive back-pressure thereto, a movable rod, a block fast thereon attached to the sylphon and in operative engagement with the indicator, a collar loose on said rod, a spring 20 acting on the collar to force it against said block, a stop in the path of the collar, a second spring acting against said block in a direction opposite to said first spring, a dash-pot cylinder and a piston on said rod working 25 in said cylinder.

30 In testimony whereof, we have hereunto signed our names.
